UNITED STATES PATENT OFFICE.

ERNEST WILSON AND CHARLES JOHN EVANS, OF LONDON, ENGLAND.

METHOD OF CONTROLLING MECHANISM BY MEANS OF ELECTRIC OR ELECTROMAGNETIC WAVES OF HIGH FREQUENCY.

SPECIFICATION forming part of Letters Patent No. 663,400, dated December 4, 1900.

Application filed July 28, 1898. Serial No. 687,083. (No model.)

To all whom it may concern:

Be it known that we, ERNEST WILSON, residing at 64 St. John's Park, Blackheath, London, and CHARLES JOHN EVANS, residing at 5 108 Castelnau, Barnes, London, England, subjects of the Queen of Great Britain, have invented a certain new and useful Method of Controlling a Mechanism by Means of Electric or Electromagnetic Waves of High Frequency, (for which we have applied for a patent in Great Britain bearing date of December 29, 1897,) of which the following is a specification.

This invention relates to improvements in 15 the apparatus used in connection with the so-called "Hertzian" waves for controlling a mechanism at a distance without the intervention of a metallic conductor; and it consists in the use of two receivers placed at 20 right angles to one another, which receivers respectively respond to a movable transmitter when the same is brought into a plane approximately parallel to the plane of the receiver and the straight line joining the centers of the two systems is approximately perpendicular to the planes of transmitter and 25 receivers, or which receivers each individually respond to separate transmitters. By this arrangement we are able to control mechanism at a distance which is in connection with 30 and operated by the two receivers at right angles.

Our invention also consists in the employment of one receiver and an instrument for 35 bringing into operative position the coherers or other contact-making devices, whereby the coherers belonging to the respective electromagnetic mechanisms can be operated in any order or combination.

40 Our invention also consists in the employment of electromagnets connected with each receiver in such manner that the magnet is magnetized by a local battery and demagnetized by the electrical impulses transmitted 45 to it from the receiver in connection with it, and may thus be used as a substitute for the coherers hitherto in use.

In order that our invention may be more 50 readily understood, we will proceed to describe its application by reference to the following drawings and show how the same may be performed.

Figure 1 is a diagrammatic view of two re-

ceivers at right angles to one another. Fig. 2 is a diagrammatic view of a movable transmitter. Fig. 3 is a diagram showing the disposition of parts to be used when it is desired to control a third circuit by means of the two receivers. Fig. 4 is a diagrammatic view of two transmitters at right angles to each other. 55 Fig. 5 is a diagram of connections, showing how a small electromagnet may be made to perform the functions of a coherer. Fig. 6 shows in detail parts of Fig. 5. Fig. 7 illustrates the manner of completing a third circuit when the two circuits of the receivers are excited simultaneously. Fig. 8 represents a mechanical means comprising a revolving commutator for completing certain circuits. Fig. 9 is a diagrammatic view illustrating separate receivers arranged one above the other, each having a separate coherer. Fig. 10 represents the wings of several receivers connected by a common coherer. Figs. 11 and 12 illustrate automatic tapping 75 means for restoring the coherers to their normal condition.

Throughout the drawings like numbers indicate like parts.

1 2 and 6 7, Fig. 1, are the receivers at right angles. The coil 4, Fig. 1, is the coil of an electromagnetic mechanism controlling the circuit 48, which may be an ordinary electromagnetic relay and which it is required to operate through the intervention of Hertzian 80 waves. This takes place when the coherer or other contact-making device 5 is actuated by the electrical impulses received by the receiver 1 2. Such action closes the circuit sufficiently at 5 and allows a current of sufficient 85 strength to flow from the battery 3 through the coil 4 of the electromagnetic mechanism. The receiver 6 7 is provided with a coherer or other contact-making device 8, a battery 9, and the coil of an electromagnetic mechanism 10, which may be an ordinary electromagnetic 90 relay controlling the circuit 50.

The conductors 11 12, Fig. 2, forming one transmitter may be of the same shape as shown at 1 and 2 in Fig. 1. They are mounted upon a horizontal shaft 13, supported in bearings 16, and capable of being turned around by means of the handle 14. The Ruhmkorff coil 15 is for the purpose of exciting the transmitter 11 12. If the plane in which the 105 transmitter 11 12 turns when the handle 14

is operated is approximately parallel to the plane of the receivers 1 2 and 6 7, Fig. 1, and the straight line joining the centers of these two systems be perpendicular to each plane, 5 the transmitter when vertical is capable of operating the circuit connected to the receiver 1 2, Fig. 1. Similarly when horizontal it is capable of operating the circuit of the receivers 6 7, Fig. 1, and in an intermediate position 10 it is capable of operating both circuits simultaneously.

The two coils 19 20, Fig. 3, are the coils of an electromagnetic mechanism which may be an ordinary electromagnetic relay. Coil 15 19 is in series with the battery 3, the coil 4, and the contact-making device 5, also shown in Fig. 1; and similarly with regard to the coil 20 and the battery 9, the coil 10, and the contact-making device 8, also shown in Fig. 20 1. When both the coherers or other contact-making devices 5 8 are acted upon by the electrical impulses received by the receivers 1 2 6 7, connected with the conductors 17 17 18 18, so as to sufficiently close the two contacts simultaneously, the electromagnetic mechanism, actuated by the coils 19 20, operates and controls the circuit 49; but otherwise it does not operate, because the current to be supplied in one coil 19 or 20 is not to be 30 of sufficient strength to operate the electromagnetic mechanism, while when both coils 19 20 are supplied with current the current-turns have sufficient strength to operate the mechanism. If preferable, we so construct 35 the electromagnetic mechanism in connection with coils 4 10 that if both are simultaneously operated a third mechanism is thereby automatically brought into operation. In this case the coils 19 20 would not be required. 40 This may be accomplished, as shown in Fig. 7, in which the third circuit 51 is completed when both coils 4 and 10 are excited simultaneously. If desirable, we may so interconnect the relays that when both are excited 45 only the circuit 51 is made.

The transmitter 11 12, Fig. 4, and the exciting Ruhmkorff coil 15 are those also shown in Fig. 2. When using stationary transmitters, we place the second transmitter 21 22, 50 excited by another Ruhmkorff coil 23, at right angles to the transmitter 11 12. This arrangement enables us to carry out the same operations as with the movable transmitter, Fig. 2—that is to say, when the plane of the 55 transmitters, Fig. 4, is approximately parallel to the plane of the receivers, Fig. 1, and the straight line joining the centers of these two systems is approximately perpendicular to each plane the horizontal transmitter 21 22 60 can be made to operate the horizontal receiver 6 7. Similarly the vertical transmitter 11 12 can be made to operate the vertical receiver 1 2. Further, when stationary transmitters are employed by the simultaneous operation of the two transmitters 11 12 and 21 65 22 the two receivers 1 2 and 6 7 can be simultaneously operated for the purpose of oper-

ating a third electromagnetic mechanism, as already set forth in connection with Fig. 3.

When using an ordinary coherer, it will probably be necessary to use a relay in its circuit; but with other contact-making devices we may use a relay or not, as may be desirable. We can, if desirable, use only one receiver at the apparatus or apparatus and bring 75 into operative position, by means of clockwork or otherwise, in any order or combination, the coherers or other contact-making devices controlling the various circuits at predetermined intervals of time. 80

In Fig. 8, 37 37 are brushes in connection with the vanes of a single receiver, which bear on commutators 38 38, which consist of metal plates fixed, as shown, to the periphery of an insulating-cylinder 39, the said cylinder being 85 rotated (at a speed suited to the particular object in view) by means of clockwork or otherwise. Between each of the pairs of plates is a coherer or other contact-making device, each of which when it is an operative position 90 in connection with the brushes 37 37 controls one of the circuits 40 41 42 43, to which it is connected by rings and brushes 44, 45, 46, and 47, as shown. We can also cause the oscillations or waves to start an operation or operations which is or are automatically performed by the mechanism or mechanisms. 95

In Figs. 5 and 6, which indicate the application of another part of our invention, 21 is a small core of steel wires, insulated from one another, wound with a solenoid 22. The terminals 17 17 of the solenoid are connected to one of the receivers, as shown in Fig. 1. A small magnet-needle is suspended by means of a fine metal conductor and sets itself in a 100 magnetic field, whose direction is determined by and is the resultant of the fields due to the small coil 21 when magnetized and an external controlling-magnet provided for the purpose, together with the earth's field unless 105 eliminated. The permanent magnet 64 (an end view of which is shown in Fig. 6) can slide on and revolve around the supporting-rod 65, fixed to the stand 27 after the manner of the adjusting-magnet of an ordinary galvanometer. 64 is diagrammatically shown in 110 Fig. 5. The sensibility and initial position of the apparatus can be varied by suitably adjusting 64. When the core 21, which is 115 used in this instance in place of a coherer, is 120 magnetized, the needle 23 is, as shown in Fig. 5, with its projection 29, resting against the stop 30. When the core is demagnetized by the impulses received by the receiver connected by the conductors 17 17 or partially 125 so, the needle 23 is deflected so as to come into contact with the contact 24, as shown by the dotted lines. This operation closes a circuit containing a battery 25, the coil 26 of an 130 electromagnetic mechanism which it is desired to operate, and the solenoid 22. The solenoid thereby magnetizes the core 21 upon which the needle 23 is deflected to its initial 135 position, as shown in Fig. 5. Fig. 6 gives de-

tails as to the way in which the apparatus may be constructed. The solenoid 22, with its core 21, rests on a small support fixed to the upright 27. In front of the solenoid 5 is suspended a magnet-needle 23, to which is attached another needle 31 in order to render the system astatic. When necessary, the system is provided with a mirror 32 in order to read by means of a spot of light and a scale 10 in the well-known manner. In order to restore the contact to its high resistance, it is necessary to tap the coherer. This we effect in a well-known manner by the intervention of the electromagnetic apparatus operated by 15 the electrical impulses, or this can be accomplished by external tapping apparatus.

A decohering arrangement is shown in Fig. 11, where 52 is a coherer which is in series with the electromagnetic mechanism or relay— 20 for example, 4 or 10—the electromagnet 53, battery 54, spring 55, and fixed contact 56, with which the spring 55 normally makes contact; but upon the coherer being cohered a current passes through the electromagnet 53, 25 which then attracts the armature 57, (fixed to the spring,) whereupon the hammer 58 hits the coherer and decoheres it and then returns to its original position, or we may arrange for some movable part of the mechanism 30 controlled to hit the coherer, or we may arrange, as in Fig. 12, a contact 63 to be made by a movable part of the apparatus at a suitable time with the result described in connection with Fig. 11, the parts being similar.

We preferably place one receiver vertically, or nearly so, so that when the transmitter is vertical or sufficiently so it will affect this receiver and its coherer or other contact-making device when it is in any part of 40 the horizontal plane in which the transmitter is or sufficiently nearly in it. These modifications forming no essential part of our invention are not illustrated. Or we can employ two or more receivers at suitable angles to 45 one another in a horizontal plane. By this method one at least of the receivers in the horizontal plane is always capable of being acted upon by oscillations or waves of suitable frequency from the transmitter. We 50 may use a coherer or other contact-making device with each receiver, as shown in Fig. 9, in which 59 indicates separate receivers arranged one above the other, each with a separate coherer 60, or one coherer or other contact-making device may be common to any or 55 all of the receivers in one plane, as shown in Fig. 11, in which 61 indicates the wings of the receivers connected to a common coherer 62.

We may suspend the system of receivers 60 preferably upon gimbals after the manner of a marine compass, so that it is always kept in the same position or nearly so relatively to the horizontal plane. If desirable, we can mount the gimbals or system, or both, on springs or 65 provide other means for damping out vibrations.

We can control a mechanism or set of mech-

anisms from one or more positions by having suitable transmitters at each, or we can control a set of mechanisms from the same transmitter, or we can control more than one mechanism or set of mechanisms simultaneously and independently by employing transmitters and receivers of different wave lengths for each. We can use a reflector on the transmitter or receiver or on each to focus or concentrate the oscillations on the receiver.

Having now described our invention, what we claim as new, and desire to secure by Letters Patent, is—

1. In a mechanism for controlling other mechanism at a distance by means of electric waves, the combination of a receiving mechanism having a pair of receivers arranged at right angles to each other, electromagnetic 85 mechanism connected with each receiver, a transmitting mechanism having transmitters arranged at right angles to one another, said transmitters being opposite to the receivers for sending electric impulses to the same, substantially as described.

2. In a mechanism for operating electromagnetic devices from a distance, the combination of receivers, coherers connected with the receivers, said receivers being arranged 95 at right angles to each other, electromagnetic mechanism connected with each coherer, a transmitting mechanism having transmitters arranged at right angles and so arranged as to be opposite to the receivers, whereby electric 100 energy can be transmitted to the electromagnetic mechanisms, substantially as described.

3. In a device for controlling mechanisms by electric waves, the combination of receivers arranged at right angles to each other, transmitters arranged at right angles to each other and in a plane parallel to the plane of the receivers and so that the line joining their centers will be approximately perpendicular to the said parallel planes, relays connected 105 with the receivers arranged at right angles to each other and contact-making devices in circuit with the said receivers, electromagnetic mechanisms connected with the relays, the construction being such that the transmitters 110 thus arranged opposite to the receivers may impart an electric impulse to either of the receivers, substantially as described.

4. In a mechanism for transmitting electrical energy, the combination of a receiving 120 mechanism having two receivers arranged at right angles to each other, electromagnetic mechanism connected with the said receivers, and transmitters arranged at right angles to each other for sending electric impulses to the 125 opposite receivers, substantially as described.

In witness whereof we have hereunto set our hands in presence of witnesses.

ERNEST WILSON.

CHARLES JOHN EVANS.
